DEVICE FOR MAKING BUTTER PATS

Maurice J. Weinberg, New York, N. Y.

Application August 10, 1948, Serial No. 43,371

17 Claims. (Cl. 31—7)

1

This invention relates to a device for making pats or chips from a block of butter, oleomargarine, or the like soft, plastic, easily incisile material.

An object of this invention is to improve the device disclosed in my co-pending application Serial No. 790,500, filed December 9, 1947, now abandoned.

In my said application, there is disclosed a device for making pats or chips, comprising a base formed with a chamber to receive a slab of butter, oleomargarine or like material and a cover which fits telescopically over the base and is provided with an integral impresser formed with ribs for dividing the slab into a plurality of separate pats or chips for impressing a design into the several pats. In said prior application, it was stated that the base could be made of molded synthetic plastics, and that the cover could also be made of such material, but that it was preferable for the cover to be made of metal so as to have a relatively high co-efficient of heat, whereby after the slab of butter is impressed, the cover could be easily removed without adherence to the slab. To make the entire cover with the impresser of metal is relatively expensive and furthermore, such a cover would be heavy to handle. Furthermore, an all metal cover with the integral impresser might get too hot, and also with such construction, it would not be possible to change the impresser design without replacing the entire cover.

It is therefore another object of the present invention to provide in a device of the character described, a cover made of synthetic plastic material, and a removable metal impresser plate, which may be readily releasably assembled with the cover, so that the weight of the cover plus impresser plate is relatively small, and whereby the impresser plate may be easily changed. With such construction, storing and shipping of alternate impresser designs involves a minimum space because the impresser plate itself is thin. Such a cover, furthermore, is easy to handle because the plastic cover serves as a heat insulator with respect to the metal impresser plate.

A further object of this invention is to provide a device of the character described, comprising a cover provided at its ends with resilient integral latching tabs formed at their inner sides with shoulders releasably engaging the under-side of an impresser plate to hold the plate against the under-side of the top wall of the cover, and said top wall being formed with

2

notches at its ends to permit engagement of said tabs from the top, so that they may be retracted to permit withdrawal of the impresser plate and replacement thereof.

Another object of this invention is to provide in a device of the character described, a cover and a removable impresser plate which may be snapped into place against the underside of the top wall of the cover by merely pressing the impresser against said underside, and said cover having means to hold the impresser plate in place within the cover.

Yet a further object of this invention is to provide a device of the character described, comprising a cover, a removable impresser plate within the cover, a knob on top of the cover, and screw threaded means on the knob screwed to the impresser plate for clamping the same against the underside of the top wall of the cover.

A still further object of this invention is to provide in a device of the character described, highly improved means to vent air from the butter chamber when the cover is telescoped over the base for impressing the slab.

Still a further object of this invention is to provide a strong, rugged and durable device of the character described, which shall be relatively inexpensive to manufacture, easy to handle and which shall yet be practical and efficient to a high degree in use.

Other objects of this invention will in part be obvious and in part hereinafter pointed out.

The invention accordingly consists in the features of construction, combinations of elements, and arrangement of parts, which will be exemplified in the construction hereinafter described, and of which the scope of invention will be indicated in the following claims:

In the accompanying drawings in which is shown various illustrative embodiments of this invention,

Fig. 1 is a front elevational view of a device embodying the invention;

Fig. 2 is an end view thereof;

Fig. 3 is a cross-sectional view taken on line 3—3 of Fig. 2;

Fig. 4 is a partial perspective cross-sectional view of a device embodying the invention;

Fig. 5 is a partial perspective end view of said device;

Fig. 6 is a bottom plan view of the cover;

Fig. 7 is a cross-sectional view taken on line 7—7 of Fig. 6;

Fig. 8 is a cross-sectional view of the cover and base taken along lines 8-8 of Fig. 6;

Fig. 9 is a partial perspective view of the base forming part of the device embodying the invention;

Fig. 10 is a partial perspective view of a cover embodying the invention and illustrating a modified construction, but with the impressor plate removed;

Fig. 11 is a longitudinal cross-sectional view through a cover and impressor plate illustrating another modified construction;

Fig. 12 is a partial perspective cross-sectional view of a device of the invention and illustrating another modified construction, and

Fig. 13 is an end view of the device embodying the invention and illustrating yet another modified construction.

Referring now in detail to the drawing, 10 designates a device embodying the invention for making pats or chips of butter, oleomargarine or the like soft plastic, easily incisile material. The same comprises generally a base 11, a cover 12 and an impressor plate 13.

The base 11 may be made in one piece of molded synthetic plastics, such as "Lucite" cellulose acetate, polystyrene, "Saran" or the like material. The base 11 comprises vertical, longitudinal front and rear walls 14 and end walls 15 and 16 interconnecting the front and rear walls. Extending outwardly from walls 14, 15 and 16 are base flanges 17 on which the base rests. The base 11, furthermore, includes a horizontal top wall 18 spaced above the base flanges 17 and interconnecting said front, rear and end walls. The front and rear walls extend above the top wall 18 of the base forming parallel longitudinal flanges 19. The flanges 19 are interconnected by an upward extension 20 of the end wall 16. The upper outer edges of flanges 19 are curved or bevelled as at 19a. The outer edge of the upper end of wall or flange 20 is likewise curved, as at 20a. Walls 14, 19 are formed at their outer surfaces with central vertical grooves 21, which extend from a point just above the base flange 17 to the upper ends of said walls. The purpose of the grooves 21 will be explained hereinafter.

The cover 12 may likewise be made in one piece and may be molded of synthetic plastic material. It comprises a top wall 25, end walls 26 extending downwardly, and front and rear walls 27 likewise extending downwardly from the top wall 25 and interconnecting the end walls 26. The cover 12 telescopically but loosely fits over the base. The top wall 25 is formed at the opposite ends thereof with notches or openings 28 centrally located with respect to the top wall and extending to the inner surface of the end walls. Said end walls 26 are each formed with a pair of slits 29 from the upper ends of said end wall down to a point above the lower ends of said end walls. The slits 29 are located at the ends of the notches 28. Thus between each pair of slits 29 is formed a tab 30 which may be sprung back by pushing outwardly against the inner surface of the upper ends of said tabs. Said tabs are resilient due to the inherent characteristics of the plastics material of which the cover is made. The cut-away portions or notches 28 permit insertion of the thumbs for engagement with the upper ends of the tabs 30 so that they may be sprung back, as shown in Fig. 5.

At the inner sides of each tab 30 is a bevelled latch portion 31 having an upwardly and in-

wardly inclined surface 32 and an upper shoulder or ledge 33. The shoulders or ledges 33 are spaced below the under-surface 25a of the top wall 25 of the cover. It will be noted that there is a clearance between the end walls 26 of the cover and the end walls 15, 16 of the base. Also, there is a clearance between the side walls 27 of the cover and the front and rear walls 14 of the base. When the cover is telescoped over the base, the curved or bevelled surface 19a, 19b and 20a facilitate mounting of the cover onto the base.

The impressor plate 13 may be made of metal and is removably and releasably locked or mounted within the cover. Said impressor plate 13 has an outline to fit snugly within the cover. Thus, the vertical corners of the cover may be rounded, and the corners of plate 13 are similarly rounded. When the plate 13 is mounted inside the cover, the ends of the plate will engage the inclined surfaces 32 of the latch portions 31 and press out the tabs 30 until the plate passes said latch portions so that the tabs 30 will snap back into place and said plate will then rest on the shoulder 33 and be locked or held against the underside of top wall 25.

The impressor plate 13 is formed all around its periphery with a flange 13a of reduced thickness. Inside the flanges 13a is an area 13b of increased thickness extending below the under-surface of said portion 13a. Said portion 13b has at its ends, opposite extensions 13c which may contact the upper edges of the side flanges 19. Said thicker portion 13b is formed with integral downwardly projecting transverse ribs or blades 13d for dividing a slab of butter or the like material into pats or chips. The slab of butter is placed on wall 18 in the chamber between the walls 19, and said slab may contact the end wall 20. A strip 40 of paper may be placed on the upper surface of wall 18 and between the flanges 19 before the slab is placed into the slab chamber. The paper strip 40 passes up and around flange 20. Said strip may be apertured so that some of the butter will contact the upper surface of wall 18. When the cover is telescoped over the base, the ends of the paper strip 40 will pass down between the end walls 26 of the cover and the end walls 15, 16 of the base, as shown in Fig. 3 of the drawing. The blades 13d will cut through the butter or like material when the cover is pushed down on the base, and the lower ends of said blades will substantially contact the paper strip 40. The plate 13 may also be formed with impressing ribs or elements 13e projecting down from its underside for impressing a design on the butter pats or chips. The impressing ribs 13e may form letters or may constitute any other suitable design.

The grooves 21 serve to vent air from the slab chamber when the cover is being fitted on to the base and pressed down. The clearance between the ends of blades 13d and the inner surface of flanges 19 is preferably greater than the clearance between the outer surfaces of walls 14 and the inner surfaces of walls 27 so that if the cover is moved around, the blades 13d will not contact the inner surfaces of flanges 19.

In Figs. 10 and 11, there is shown a cover 50 embodying the invention and illustrating a modification thereof. The cover 50 may be used in conjunction with a base 11, such as described above, except for one change which will be explained. The cover 50 has a top wall 51, end

walls 52 and front and rear walls 53. The walls 53 may be formed at their inner surface with vertical central ducts or grooves 54, extending down to the lower edges of said walls and terminating just short of the top wall 51. The top wall 51 may be formed with a through opening 55. Contacting the undersurface of top wall 51 is impressor plate 56 which may be exactly the same as the impressor plate 13 except that it is formed with a central screw threaded opening 57. Means is provided for removably attaching impressor plate 56 to the underside of top wall 51. To this end, there is provided a knob or handle 58 formed with a central screw threaded stem 59 projecting through the opening 55 and screwed into the threaded opening 57 of plate 56. When the knob 58 is tightened, it will press the plate 56 against the underside of top wall 51. The knob 58 serves as a handle for the cover and is also a means for attaching the impressor plate to the cover. The impressor plate 56 may be released by unscrewing the handle 58.

Since the cover 50 is formed with the grooves 54, the base 11 used in conjunction therewith may omit the grooves 21, which serve the same purpose.

In Fig. 12 there is shown a device 60 embodying the invention and illustrating yet another modified construction. In the device 60 there is employed a base 11, which may be the same as that described in Figs. 1 to 9. Also, there may be employed in connection with the device 60, an impressor plate 13, similar to the one described hereinabove. There is also employed a cover 61 similar to the cover 12 except that instead of latch 31 for tabs 30 there is provided a transverse bead 62. The ends of the plate 13 push back against beads 62 and snap over the upper edge of the beads so as to be held in place thereby. It will be noted that the plate 13 may be removed by merely pressing back on the tabs 30 sufficiently for the latch 31 or bead 62 to clear the ends of the impressor plate.

In Fig. 13 there is shown a device 65 embodying the invention and illustrating yet another modified construction. In the device 65, there is employed a cover 66 similar to the cover 12, with the exception that there is substituted for tabs 30 of cover 12, tabs 30a hinged to the end walls of the cover by means of spring hinges 67. Otherwise the device 65 is the same as the device 10.

It will be noted that the walls 27 of the cover 12 are formed at the lower edges with central notches 27a to receive the fingers of the user for facilitating lifting of the cover off the base.

It will be noted that if the tabs 30 are raised above the top wall 25 of the cover, the notches 28 may be eliminated, since in such case the upwardly projecting portion of the tabs may be engaged for pushing the tabs apart to permit the impressor plate 13 to fall out of the cover.

Grooves 21 and 54 may be omitted if desired, since air will be vented by reason of the engagement of wings 13c with the upper edges of the flanges 19 and furthermore, air may escape through the slits 29. When the beads 62 are employed, as in Fig. 12, the tabs 30 need not be pressed apart to release the plate 13. Instead, thumbs may be inserted through the notches 28 and pressure applied downwardly against the portions of the impressor plate 13, exposed by the notches, to cause engagement of the ends of the plate with said bead for pressing the tabs 30 apart. The impressor plate 13

is easily removable for the additional purpose that it may be cleaned and replaced for sanitary purposes. The plates 13b may be centrally notched, as at 13e, if desired.

It will now be understood that the covers may be made of synthetic plastic whereas the impressor plate may be made of metal. The cover acts as an insulation against the heat of the metal plate. The plate is interchangeable so that various designs may be stocked. These plates are relatively thin so that they may be compactly shipped and stored. The cover together with the plate is light and easy to handle and is relatively inexpensive to manufacture.

In using the device 10, the cover may be dipped in hot water so that the impressor plate will be warmed sufficiently to prevent it from sticking to the butter. The cover itself, however, is made of plastic, which does not have a high specific heat. The metal plate will hold its heat while the cover will remain cool so that it will be easy to handle.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all matter herein set forth or shown in the accompanying drawings is to be interpreted as illustrative and not in a limiting sense.

Having thus described my invention, I claim as new and desire to protect by Letters Patent:

1. A device for making pats from a slab of butter or the like soft plastic material, comprising a base member having a chamber to receive the slab, a cover member telescopically fitted over the base and an impressor plate removably mounted in a fixed position within the cover member and adapted to press against the top of the slab, the cover member being made of synthetic plastic material and the impressor plate being made of metal, at least one of said members being formed with ducts disposed between the sides of the cover member and base member.

2. A device for making a plurality of pats from a slab of butter or the like soft plastic material, comprising a base having a chamber to receive the slab, a cover telescopically fitted over the base, and an impressor plate removably mounted within the cover, said cover and base being formed with air ducts between the walls thereof and adapted to press against the top of the slab, said cover being made of non-metallic material, and said impressor plate being made of metallic material.

3. A device for making pats from a slab of butter or the like soft plastic material, comprising a base having a chamber to receive the slab, a cover telescopically fitted over the base, an impressor plate adapted to press against the top of the slab, and resilient means on the ends of the cover for latching the plate to the cover, by forming a tight fitting shelf therefor at both ends of said cover.

4. A device for making pats from a slab of butter or the like soft plastic material, comprising a base formed with a chamber adapted to receive the slab, said chamber being open at the top and having an upper surface, a cover telescopically fitted over the base and comprising a top wall and walls projecting downwardly from said top wall, an impressor plate, means for re-

movably mounting the plate within the cover in a fixed position and against the underside of said top wall, for impressing the top of a slab within said chamber and for dividing the same into pats, said impressor plate having means to divide the slab into pats, extending substantially down to the upper surface of said chamber.

5. A device for making pats from a slab of soft plastic material, comprising a base formed with a chamber adapted to receive the slab, said chamber being open at the top, a cover telescopically fitted over the base and comprising a top wall and walls projecting downwardly from said top wall and an impressor plate removably mounted within the cover and against the underside of said top wall for impressing the top of a slab within said chamber and for dividing the same into pats, said base and cover being made of non-metallic material and said impressor plate being made of metal, said impressor plate having shouldered end portions which rest upon bosses extending from the end walls of said cover.

6. A device for making pats from a slab of soft plastic material, comprising a base formed with a chamber adapted to receive the slab, said chamber being open at the top, a cover telescopically fitted over the base and comprising a top wall and walls projecting downwardly from said top wall, an impressor plate, means releasably retaining said plate within the cover and against the underside of said top wall of the cover for impressing the top of a slab within said chamber and for dividing the same into pats, said top wall being provided with cutaway portions adjacent said retaining means, said impressor plate being made of material having a higher specific heat than said base and cover.

7. A device for dividing a slab of butter or material of the like consistency into pats, comprising a base formed at its upper end with a chamber open at the top and adapted to receive said slab, a cover fitted telescopically over said base and having a top wall and downwardly projecting end, front, and rear walls, said end walls including spring slabs, an impressor plate, and means on said spring tabs for holding said impressor plate against the underside of said top wall of the cover.

8. A device for dividing a slab of butter or material of the like consistency into pats, comprising a base formed at its upper end with a chamber open at the top and adapted to receive said slab, a cover fitted telescopically over said base and having a top wall and downwardly projecting end, front, and rear walls, said end walls including spring tabs, an impressor plate, and means on said spring tabs for holding said impressor plate against the underside of said top wall of the cover, said tabs being integrally formed with said end walls.

9. A device for dividing a slab of butter or material of the like consistency into pats, comprising a base formed at its upper end with a chamber open at the top and adapted to receive said slab, a cover fitted telescopically over said base and having a top wall and downwardly projecting end, front, and rear walls, said end walls including spring tabs, an impressor plate, and means on said spring tabs for holding said impressor plate against the underside of said top wall of the cover, said tabs being hinged to said end walls.

10. A device for dividing a slab of butter-like material into pats comprising a base member having front, rear, and end walls and a top wall,

and front and rear flanges extending above said top wall and forming a chamber to receive said slab and a cover member telescopically fitted over said base and having a top wall, end walls and front and rear walls, an impressor plate releasably latched in a fixed position to the underside of the top wall of said cover, and resilient means on the cover and engageable with said impressor plate to releasably latch said impressor plate to the underside of the top wall of said cover.

11. A device for dividing a slab of butter-like material into pats comprising a base member having front, rear and end walls and a top wall, 15 and front and rear flanges extending above said top wall, and forming a chamber to receive said slab, and a cover member telescopically fitted over said base and having a top wall, end walls and front and rear walls, an impressor plate releasably mounted in a fixed position at the underside of the top wall of said cover, the front and rear walls of one of said members being formed with vent grooves on the surface thereof, facing the front and rear walls of the other member to vent air which might otherwise be trapped in said slab chamber when pushing the cover down on the base to impress a slab therein by means of said impressor plate, said impressor plate having ridges extending substantially down to the top wall of the cover to divide the slabs into pats.

12. A device of the character described, comprising a base, a member telescopically fitted over the base and comprising a top wall and walls projecting downwardly from said top wall, said top wall being formed with openings at its ends, an impressor plate contacting the underside of said top wall, means having their upper edges in the openings in said top wall flush therewith for removably attaching said plate to the underside of said top wall, said plate attaching means including a portion extending below the top wall of said member and forming a shoulder on the inner ends of said member.

13. A device for making pats from a slab of butter or the like soft plastic easily incisible material, comprising a base having a chamber to receive the slab, a cover telescopically fitted over the base and an impressor plate removably mounted within the cover and said cover and base being formed with air ducts between said base and cover and adapted to press against the top of the slab, said impressor plate being of a material having a higher heat conductivity than the material of said cover.

14. A device for dividing a slab of butter or material of the like consistency into pats, comprising a base formed at its upper end with a chamber open at the top and adapted to receive said slab, a cover fitted telescopically over said base and having a top wall and downwardly projecting end, front, and rear walls, said end walls including spring tabs, an impressor plate, and means on said spring tabs for holding said impressor plate against the underside of said top wall of the cover, said top wall being formed with notches extending to the tab portion of said end walls.

15. A device for dividing a slab of butter or material of the like consistency into pats, comprising a base formed at its upper end with a chamber open at the top and adapted to receive said slab, a cover fitted telescopically over said base and having a top wall and downwardly projecting end, front, and rear walls, said end walls

including spring tabs, an impressor plate, and means on said spring tabs for holding said impressor plate against the underside of said top wall of the cover, said top wall being formed with notches extending to the tab portion of said end walls, said cover having a pair of opposite walls, the lower edges of which are notched to receive fingers of the user, to facilitate lifting the cover off the base.

16. A device for making a plurality of pats from a slab of butter or the like soft, plastic, easily incisible material, comprising a base having a chamber to receive the slab, a cover having a top, and two vertical end walls and two vertical side walls extending downwardly therefrom, telescopically fitted over the base, an impressor plate removably mounted in a fixed position within said cover, and adapted to press against the top of the slab, and means on the cover engageable with said impressor plate to retain said impressor plate within the cover, a cutaway portion in the top of the cover surrounding the top edge of said retaining means.

17. The device of claim 16 in which said means comprises resilient tabs, each tab being formed with an inwardly projecting shoulder in contact with the underside of said impressor plate, which rests thereon, air ducts formed between said

plate's sides and the inner vertical sides of said cover.

MAURICE J. WEINBERG.
